GB 1 360 058 7/1974

* cited by examiner

Primary Examiner—Mitchell Siegel(74) Attorney, Agent, or Firm—McKee, Voorhees & Sease, P.L.C.(57) CLAIM

I claim the ornamental design for a golf club head cover, substantially as shown and described.

DESCRIPTION

FIG. 1 is a perspective view of the golf club head cover.

FIG. 2 is a bottom elevational view of the golf club head cover.

FIG. 3 is a top elevational view of the golf club head cover.

FIG. 4 is a back elevational view of the golf club head cover.

FIG. 5 is a front elevational view of the golf club head cover; and,

FIG. 6 is a side elevational view of the golf club head cover.
